(57) **CLAIM**

The ornamental design for a paving stone as shown and described.

DESCRIPTION

1.1 is a top plan view of a paving stone according to a first embodiment;

1.2 is a left side view thereof;

1.3 is a right side view thereof;

1.4 is a bottom plan view thereof; and

1.5 is a top perspective view thereof.

2.1 is a top plan view of a paving stone according to a second embodiment;

2.2 is a left side view thereof;

(Continued)

2.3 is a right side view thereof;
2.4 is a top perspective view thereof; and
2.5 is a bottom plan view thereof.
3.1 is a top perspective view of a paving stone according to
a third embodiment;
3.2 is a left side view thereof;
3.3 is a top plan view thereof;
3.4 is a bottom plan view thereof; and
3.5 is a right side view thereof.
